CLAIM

The ornamental design of the combined drink bottle and lid, as shown and described.

DESCRIPTION

FIG. 1 is a perspective view taken from the upper, front, right-hand side of the combined drink bottle and lid;

FIG. 2 is a perspective view taken from the lower, front, left-hand side of the combined drink bottle and lid of FIG. 1;

FIG. 3 is a front elevational view of the combined drink bottle and lid of FIG. 1;

FIG. 4 is a side elevational view of the right side of the combined drink bottle and lid of FIG. 1;

FIG. 5 is a back elevational view of the combined drink bottle and lid of FIG. 1;

FIG. 6 is a side elevational view of the left side of the combined drink bottle and lid of FIG. 1;

FIG. 7 is a top plan view of the combined drink bottle and lid of FIG. 1; and,

FIG. 8 is a bottom plan view of the combined drink bottle and lid of FIG. 1.

The broken lines illustrate portions of the combined drink bottle and lid which form no part of the claimed design.

1 Claim, 8 Drawing Sheets
